UNITED STATES PATENT OFFICE.

CLARENCE E. LANE, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONIC APPARATUS.

Application filed July 12, 1923. Serial No. 651,005.

This invention relates to telephonic apparatus and particularly to devices for aiding the hearing of partially deaf persons, these devices being generally known as audio-phones or deaf sets.

5 The object of the invention is in general to provide a convenient form of deaf set which does not hamper the movements of the user and which will enable him to hear 10 distinctly weak sounds coming from any direction.

In previous forms of electrical deaf sets, the transmitter has either been placed upon a desk or table near the user or has been 15 hung upon the front of the coat or vest of the user. The first form of apparatus considerably hampers the movements of the user and the second form makes it necessary for the user to face the source of weak 20 sounds in order to hear them distinctly. This is awkward and inconvenient and often it is difficult for the user to get into such a position that the sounds will impinge directly upon a transmitter hung upon the 25 front of his coat or vest.

The present invention overcomes these difficulties by providing a deaf set in which the transmitter is mounted upon the wrist of the user and hence may be quickly moved 30 to a position such that sounds coming from any direction will impinge directly upon it, while at the same time leaving the user the greatest freedom of movement.

Referring to the drawing:

35 Fig. 1 shows schematically a suitable circuit arrangement of the deaf set.

Fig. 2 shows the manner in which the deaf set is carried or worn by a user, and,

40 Fig. 3 shows the transmitter with means for securing it to the wrist of the user.

Referring to Fig. 1, transmitter 1 is supplied with direct current by a battery 2 which also supplies current to energize the filaments of amplifying tubes 3 and 4 45 through the variable resistance 5. Amplifying tubes 3 and 4 are coupled in a well known manner by transformer 5 and comprise a well known form of two stage amplifier. Voltage for the output circuits of 50 the tubes is supplied by battery 6 connected as shown. When a sound impinges upon transmitter 1, it causes a variation in its resistance thus causing a corresponding alternating E. M. F. to be induced in the secondary 55 of transformer 7. This E. M. F.

after being amplified in a well known manner by tubes 3 and 4 is impressed upon the circuit containing receiver 8, thus causing the receiver to reproduce the sound with sufficient strength for it to be clearly heard 60 by one partially deaf. The primary of transformer 7 is shunted by a variable resistance 9 which can be adjusted to regulate the voltage applied to the amplifiers and hence regulate the volume of the sound of 65 the receiver, to a value which is comfortable for the user.

The entire apparatus with the exception of the transmitter and receiver is arranged in a case 10 which may be placed in the 70 pocket of one using the invention. The top of case 10 is provided with binding posts for attachment of the conductors leading to the transmitter and the receiver. The receiver 8 may be conveniently secured adjacent the ear of the user by a head band 11 and may be connected to the apparatus by means of a duplex cord 12 which passes under the wearer's coat at the collar and hence is quite inconspicuous. The transmitter 75 1 may be of any suitable form provided at its base with metallic loops 13 through which is passed a strap 14 having a buckle 15 by means of which it may be conveniently attached to the wrist of the wearer. A 80 leather flap 16 sewed to the strap covers the metallic loops 13 and prevents them from being felt by the user. The transmitter may be conveniently connected to the apparatus by means of a duplex cord 17 which passes 85 through the wearer's sleeve and hence is wholly concealed.

It is seen that the deaf set of the present invention is quite inconspicuous when being worn and leaves the wearer the greatest possible freedom of movement. The wearer 90 can quickly point the transmitter in any direction thus enabling him to hear relatively weak sounds. In case the wearer is very 95 hard of hearing the transmitter may be 100 readily placed in front of the lips of one with whom he is conversing thus enabling him to clearly understand him.

What is claimed is:

1. A deaf set comprising a telephone 105 transmitter and a telephone receiver, means to hold the receiver adjacent the ear of a user, and means to attach the transmitter to the wrist of a user in a relatively fixed relation to the wrist of a user.

2. A deaf set comprising a telephone transmitter and a telephone receiver, means to hold the receiver adjacent the ear of a user, and a wrist strap attached to the transmitter for securing it in a relatively fixed relation to the wrist of a user.
3. A deaf set comprising a telephone receiver and means for associating said receiver with the ear of the user, a telephone transmitter and means for securing the said transmitter in a fixed relation to the wrist of the user, and circuit for operatively connecting said transmitter to said receiver.
4. A deaf set comprising a telephone receiver and means for associating said receiver with the ear of the user, a telephone transmitter and means for securing the said transmitter in a fixed relation to the wrist of the user, circuit for operatively connecting said transmitter to said receiver, and a source of energy in said circuit adapted to be carried by the user.

In witness whereof, I hereunto subscribe my name this 3 day of July, A. D. 1923.

CLARENCE E. LANE.
